UNITED STATES PATENT OFFICE.

LOUIS LAPERSONNERIE, OF NEW YORK, N. Y.

CONCRETE WALL CONSTRUCTION.

959,360.

Specification of Letters Patent. Patented May 24, 1910.

Application filed March 8, 1909. Serial No. 482,006.

To all whom it may concern:

Be it known that I, LOUIS LAPERSONNERIE, a citizen of the United States, and a resident of the city of New York, borough of Brooklyn, in the county of Kings and State of New York, have invented a new and Improved Concrete Wall Construction, of which the following is a full, clear, and exact description.

10 The object of the invention is to provide a new and improved concrete wall construction, arranged to provide suitable furring strips for fastening door frames, base boards, picture moldings and the like securely in place on the wall, the said furring strips forming integral parts of the blocks of concrete or other plastic material.

15 A practical embodiment of the invention is represented in the accompanying drawings forming a part of this specification, in which similar characters of reference indicate corresponding parts in all the views.

Figure 1 is a perspective view of the improvement; Fig. 2 is a similar view of a modified form of the same; Fig. 3 is a front end view of one of the base blocks; Fig. 4 is a side elevation of the same; Fig. 5 is a rear end view of the same; Fig. 6 is a sectional plan view of the same on the line 30 6—6 of Fig. 4; Fig. 7 is an end view of the base block wall construction shown in Fig. 2; Fig. 8 is a side elevation of the same; Fig. 9 is a plan view of the end furring strip and its anchor; Fig. 10 is a plan view of 35 one of the blocks having air spaces; Fig. 11 is a sectional plan view of a modified form of the base block; and Fig. 12 is a cross section of one of the furring strips for the block shown in Fig. 11.

40 The wall shown in Fig. 1 is formed of base blocks A, intermediate courses of concrete blocks B and a course of top blocks C, and each base block A has embedded in it opposite longitudinal furring strips D, preferably made of wood and of dovetail shape, so as to form an integral part of the block without danger of pulling out of the same. The longitudinal furring strips D of each block A are connected with each other by 45 cross bars D', preferably notched, as indicated in Fig. 6, to assist in holding the longitudinal furring strips D against pulling out of the block in a lateral direction. Each base block A is also provided on each 50 face with vertically disposed furring strips E, preferably of dovetail shape and extend-

ing from the bottom of the block to within a distance of the longitudinal furring strips D. By the arrangement described the base board can be readily secured in place on the furring strips D and E by the use of nails, screws or other fastening devices.

55 In the outer ends of the blocks A and B at the door and window openings are embedded vertically disposed furring strips F to which the door casings are secured by suitable fastening devices, each furring strip F being preferably of dovetail shape at the sides and ends, as indicated in Figs. 3, 4 and 6, and the outer faces of the furring strips F are flush with the ends of the blocks A and B, and the sides, top and bottom of the furring strips F terminate distances from the corresponding sides, top and bottom of the blocks A and B, as will be readily understood by reference to Figs. 1 and 3. Each furring strip F is provided at its back with a staple F' (see Figs. 4, 6 and 9) on which is fulcrumed an anchor F² 60 embedded in the concrete material of the block A or B. By this arrangement the furring strip F is securely held against pulling out of the block in addition to the dovetail sides and ends of the furring strip.

65 Each upper block C is provided with a furring strip G extending longitudinally and embedded in the corresponding side of the block C, to allow of fastening picture moldings and the like to the furring strip the desired distance from the ceiling. The furring strips G are projected a distance beyond the face of the block C, and the base blocks A are provided with offsets A' a distance above the furring strips D so as to provide space for the plaster H to extend 70 from the flange A' to the furring strip G, thus rendering the face of the plaster H flush with the sides of the base blocks A and the furring strips G. The level I, shown in Fig. 1, shows that the faces of the furring strips D and G lie in the same vertical plane, and a sufficient space is provided between the shoulders or flanges A' and the projecting portions of the furring strip G 75 to accommodate a desired thickness of the plaster H.

80 In order to provide continuous furring strips D and G along the base and the upper portion of the wall, the furring strips are 85 slightly projected beyond the ends of the blocks A, so as to accommodate the cement or other binding material J used between 90

adjacent blocks, to unite the same. As indicated in Figs. 2, 7 and 8, the base blocks A², the intermediate blocks B' and the upper blocks C' are all of the same thickness, and 5 in this case the longitudinal furring strips D² for the base blocks A² project beyond the sides thereof similarly to the furring strips G' in the upper blocks C', and in this case the plaster H' is applied to the wall between the projecting portions of the furring strips D² and G', to render the face of the plaster flush with the faces of the furring strips D² and G'.

In the modified form shown in Fig. 11, 15 the block K is provided on its sides with vertically-disposed grooves K', for receiving furring strips L to be inserted in the grooves K'.

From the foregoing it will be seen that 20 by the arrangement described the furring strips form integral parts of the corresponding concrete blocks and are securely embedded therein, so as to prevent the furring strips from pulling out under strain.

25 It is understood that although I have particularly referred to concrete blocks, the invention is applicable to blocks of plaster of paris, or other plastic materials.

Having thus described my invention, I 30 claim as new and desire to secure by Letters Patent:

1. A concrete block provided with a longitudinal furring strip embedded in one face thereof and having extensions projecting beyond the ends of the same, said extensions forming a continuous nailing strip over the joint and producing a spacing means for the blocks, a plurality of vertical furring strips embedded in the block below the longitudinal strips, and a furring strip embedded in one end of the block, said strip being spaced from the sides, top and bottom of the block.

2. A concrete block provided with furring strips embedded in opposite sides of the 45 block and having extensions projecting beyond the ends of said block, said extensions

forming a continuous nailing strip over the joint and producing a spacing means for the blocks, and transverse bars connecting the said strips.

3. A concrete block provided with a longitudinal strip embedded in one face thereof and having its ends projecting beyond the ends of the block, said projecting ends forming a continuous nailing strip over the joint 55 and producing a spacing means for the blocks, and a plurality of vertical furring strips in the said face of the block below the longitudinal furring strip.

4. A concrete block provided with a longitudinal furring strip embedded in a face of the block and projecting beyond the ends thereof, whereby provision is made for properly spacing the blocks and forming a continuous strip over the joint of the blocks.

5. A concrete block provided with a longitudinal furring strip embedded in a face of the block and projecting beyond the ends thereof, the furring strip being dovetailed, the projecting ends of the strip serving as a 70 means for spacing the blocks and forming a continuous strip over the joint of the blocks.

6. A concrete wall, comprising blocks, the base block having its upper portion reduced in thickness, a shoulder being formed at the 75 base of the reduced portion, and the other blocks being of the same thickness as the reduced portion of the base block, longitudinal furring strips embedded in the base blocks below the shoulder thereof and flush 80 with the face of said blocks, and a longitudinal furring strip embedded in the upper blocks and projecting from the face of said blocks.

In testimony whereof I have signed my 85 name to this specification in the presence of two subscribing witnesses.

LOUIS LAPERSONNERIE.
